(57) CLAIM

The ornamental design for an operating grip for endoscopic treatment tool, as shown and described.

DESCRIPTION

FIG. 1 is a top, front and left side perspective view of an operating grip for endoscopic treatment tool showing my new design;

FIG. 2 is a top, rear and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a top, rear and right side reference perspective view showing the state of attaching a flexible sheath, a treatment part, and an operation wire;

FIG. 10 is a top, rear and right side reference perspective view thereof in a manner of use;

FIG. 11 is a reference front elevational view showing the state of advancing a tip portion with respect to a grip body; and,

FIG. 12 is a reference front elevational view showing the state of rotating a finger hook operation member with respect to the grip body.

The broken lines shown in FIGS. 9 and 10 are for the purpose of illustrating environmental subject matter and form no part of the claimed design.

The dash-dash broken lines in FIG. 12 are for purposes of illustrating portions of the operating grip for endoscopic treatment tool that form no part of the claimed design.

The dot-dash broken lines in FIG. 12 depict a boundary of the claimed design and form no part thereof.

1 Claim, 11 Drawing Sheets
